UNITED STATES PATENT OFFICE.

MORRIS S. WRIGHT, OF WORCESTER, MASSACHUSETTS, ASSIGNOR TO M. S. WRIGHT COMPANY, OF WORCESTER, MASSACHUSETTS, A CORPORATION OF MASSACHUSETTS.

COMBINED VACUUM-CLEANER AND CARPET-SWEEPER.

1,109,492.

Specification of Letters Patent.

Patented Sept. 1, 1914.

Application filed May 10, 1913. Serial No. 766,870.

To all whom it may concern:

Be it known that I, MORRIS S. WRIGHT, a citizen of the United States, residing at Worcester, in the county of Worcester and 5 State of Massachusetts, have invented certain new and useful Improvements in Combined Vacuum-Cleaners and Carpet-Sweepers, of which the following is a specification, reference being had therein to the accompanying drawing.

This invention relates to carpet cleaning machines of a portable type adapted to be moved back and forth over a floor or other surface, and in its movement to gather up 15 dust and the like from said surface.

In an effort to combine, in a single machine, some of the advantages of a "sweeper" and "vacuum cleaner" it has been suggested to attach to the vacuum 20 cleaner, a brush or the like, but this type of construction did not prove altogether satisfactory in practice, since the brush attachment did not take the form of a true carpet sweeper, and it was impossible to utilize the 25 brush attachment as a sweeper independently of the vacuum cleaner. This had disadvantages in that it was deemed not desirable at all times to utilize at the same time, both the vacuum cleaner and sweeper, and 30 this led to the present invention.

More particularly, the present invention is 35 designed to combine in a single machine, a suction cleaning device and a sweeping device, one of said devices being adapted to be connected to the other and being detachable as a complete unit from the other, to the end that when combined, the devices operate together as a single machine, thereby combining the advantages of the sweeper 40 and suction cleaner, and the parts being constructed and arranged whereby when the detachable device is removed, the two devices may be independently operated, the one as an ordinary carpet sweeper, and the 45 other as a suction cleaner. Therefore, the present invention may be said to include in combination, a portable vacuum cleaner adapted to move back and forth over the floor and having connected thereto a carpet 50 sweeper, the latter being operated by the

movement and operation of the vacuum cleaner, and being detachable therefrom, whereby the sweeper or suction device may be operated jointly and also independently.

A further important characteristic of the 55 invention resides in novel supporting means on the vacuum cleaner for the sweeper, whereby the latter will at all times assume and maintain a correct operative position relative to the surface, and this, without in 60 any way interfering with the maintenance of proper contact between the inlet end of the dust nozzle of the vacuum cleaner and the floor surface. With this aim in view, the connection between the sweeper and 65 vacuum cleaner is a movable one, permitting the sweeper device to independently move in a vertical direction and in the preferred embodiment of my invention the connection is such that the sweeper device will 70 of its own weight assume a lowered position in working contact with the surface.

It is further contemplated by the invention to provide a sweeper which, while of 75 itself a complete operative device for customary sweeping purposes, is of a size to fit substantially within the space between the usual downwardly projecting nozzle inlet at one end and the supporting wheel at the opposite end of the vacuum cleaner, 80 the casing of the latter constituting in effect a covering or housing for the sweeper, and the combined devices occupying but little more space than one of said devices as at present constructed.

Again, the invention includes means whereby a single operating handle may be employed for imparting movement to either the suction cleaner or carpet sweeper, the handle being readily removable from the 90 suction cleaner, when it is desired to utilize the carpet sweeper by itself, and the handle having means of attachment to said carpet sweeper when detached.

It is a further object of the invention to 95 provide a simple, inexpensive and highly efficient machine of the character mentioned adapted to thoroughly and effectively remove not only the finer particles of dust and dirt from a carpet or the surface under 100

the carpet, but to further cleanse the carpet itself of threads, lint, hair, pins and other heavier particles.

The above improvements as well as others 5 and novel details in the construction and arrangement of parts will be brought out with more particularity in the description to follow, which for a clear understanding of the invention is to be considered in connection 10 with the accompanying drawings forming a part hereof, and wherein is disclosed for the purpose of illustration a convenient and satisfactory embodiment of the invention.

In the drawings, Figure 1 is a side elevation of the combined machine. Fig. 2 is a longitudinal section of the machine, parts being shown in elevation. Fig. 3 is a top plan view of the sweeping device, with the cover open. Fig. 4 is a detail view of the 20 handle coupling members detached.

With more particular reference to the drawings, wherein like reference numerals refer to corresponding parts throughout the several views, the vacuum or suction cleaner 25 device will first be referred to.

1 is the bottom wall of a suitable dust box, the top wall 2 of which is preferably inclined in a downward direction from the front end thereof. 3 are the side walls of the dust box 30 and a vertically extending wall 4 forms the rear end of said box, the opposite or front end of which is open to receive the collected dust. Supported upon the top wall 2 of the dust box are suitable bellows 4' comprising a lower stationary wall and an upper movable wall, the walls being hingedly connected at the front end of the machine and being otherwise connected by flexible folds 5. The fixed bottom wall of the bellows is adapted 40 to have valved communication as at 6 with the interior of the dust box and the upper movable wall has a valve controlled outlet 7. Conveniently a pair of bellows are employed, the same being oppositely acting to the end 45 that as one is expanded the other is collapsed, the driving means for the bellows taking the form of suitable pitman rods each pivotally connected at 9 to the movable wall of the bellows and having an eccentric connection 10 with a drive shaft 11 extending transversely of the machine. A suitable traction wheel 12 is supported on the drive shaft 11. The traction wheel 12 may have a rubber or other frictional tread surface 13. 55 The bellows are of a length to extend substantially from end to end of the machine and overlie the traction wheel as shown, the top and bottom walls of the dust box being extended to a point adjacent the rear end 60 of the machine and conveniently cut out to receive the traction wheel and pitman connections.

14 is a removable cover for the bellows,

the same forming in connection with the side walls 3 and rear end wall 15 an inclosing 65 casing.

16 is a flexible dust collecting and filtering bag, having at its open mouth end thereof a surrounding collar 17. The collar has at opposite sides thereof a bow spring 18 fixedly connected at one end as by screws 19 and slidably connected at the opposite free end. The said bow springs are adapted to yieldably engage an adjustable abutment in the form of a threaded bolt 20 projecting 75 forwardly from suitable side flanges 21 on the walls 3 adjacent the forward end of the dust box. The dust inlet nozzle preferably takes the form of a body part 22 extending substantially from side to side of the machine and having a dust inlet mouth 23 with an elongated intake slot 24 at the lower edge thereof. The nozzle is removably mounted, preferably by a suitable swinging bail 24 mounted upon the casing and adapted to be 80 moved into and out of engagement with bow springs 25 secured at one end to the body part of the nozzle 22 and free at the opposite end. The nozzle when engaged by the bail 24 will be forced into yieldable contact 85 with the wall surrounding the opening of the dust box. The yieldable action of the springs 18 in forcing the collar outwardly so as to be engaged by the nozzle may be adjusted by the bolts 20.

Pivotaly mounted upon the sides of the casing as by brackets 26 is a suitable handle bail 27 having a cup shaped coupling member 28 inferiorly threaded at 29 adapted for the reception of a removable handle 30 having exterior threads 31 to engage with threads of the cup shaped member 28. Extending longitudinally of the sides of the cover 14 are suitable bow springs 32 secured at one end 33 and slidably connected at 34 105 and having a retaining recess 35 intermediate said ends. The said recesses 35 are adapted to receive the arms of the handle bail 27 and retain the same in a fixed position when the device is not in use. This connection has been found to be particularly advantageous in the application and removal of the nozzle, since in this process it is customary to tilt the machine upon the rear end thereof to the end that the nozzle and 110 dust bag may be removed vertically, thereby obviating any spilling of the collected dust.

From the description thus far, it will be appreciated that a complete suction cleaning device is provided, the same being adapted 120 to be operated by engaging the handle 30 and imparting back and forth movement to the machine over the surface, the bellows alternately acting through their drive connections with the traction wheel 12 to suck 125 up the dust and other lighter particles from

the floor covering, or through the floor covering and from the surface of the floor itself. It will also be appreciated that a space is left between the wheel chamber at the rear 5 end of the device and the projecting mouth or inlet end of the nozzle at the front of the device, and I conveniently take advantage of this space for the reception of the carpet sweeper to be now described.

- 10 36 are side walls of a suitable casing for the sweeper, the end walls of which are designated by the reference numeral 37, and the bottom walls 38 of which take the form of dust pans inclining from said ends toward the center of the device and terminating short of said center and having upwardly extending struck up dust retaining lips or flanges 39. The flanges 39 are preferably curved, and the space therebetween 15 is adapted for the reception of a suitable brush 40 mounted upon a shaft 41 which said shaft has bearing at its ends in side guard plates 42 slightly spaced from the sides 36 of the sweeper device. The sides 20 36 are preferably slotted at 43 for the ready application and removal of the brush and its shaft from said side plates 42. The driving means for the brush shaft takes the form of traction wheels 44, there being a 25 pair at each side of the brush having rubber or other friction treads 45. The said wheels are positioned in the space between the sides 36 of the casing and the guard plates 42 and are mounted upon suitable shafts 46 30 extending from side to side of the machine and loosely supported in slots 47 in the sides 36. Suitable spring members 48 connected to the ends 37 of the casing are adapted at their free ends 49 to normally 35 exert inward and downward pressure on the rollers whereby to tend to force the same into contact with the floor surface as well as into contact with suitable transmission wheels 50 having rubber or other yieldable treads 51, the said transmission wheels 40 being mounted upon the brush shaft 41, one adjacent each end thereof in the space between the sides 36 and guard plates 42. A movable top or cover 51 conveniently of sheet 45 metal is pivotally connected at one end 52 to one end 37 of the casing and has an engaging lip 53 at the opposite end thereof to slip over and engage a suitable spring member 54 forming a latch whereby to maintain 55 the cover in place. A handle bail 55 is pivotally connected at 56 to the sides 36 of the casing, the opposite arms of said bail being adapted to lie within the space between the wheels 44 and the sides 36 of the casing. 60 The sweeper as above described is adapted to fit below the dust box in the space between the nozzle and wheel chamber and is preferably movably supported in position

as by pintles 57 and 58, the one being secured to and projecting inwardly from a downwardly projecting part 59 of the vacuum cleaner casing and the other projecting inwardly from the nozzle member 23. The ends 37 of the sweeper casing are provided with vertically extended recesses or slots 60 65 70 adapted for the reception of the said pintles 57 and 58. This connection makes possible the automatic positioning of the sweeper relative to the surface, and because of the loose connection between the sweeper device 75 and vacuum cleaner, the contacting engagement of one or the other of the parts comprising the sweeper drive wheels and the nozzle, will not interfere with the engagement of the other with the surface to be 80 cleaned.

Suitable buffers 61 secured to the under surface of the bottom wall 1 of the dust box prevent injurious contact between the top of the sweeper and the bottom of the 85 dust box, and likewise deaden the sound between these parts in the operation of the device.

As has been seen, the removable nozzle 22 constitutes a retaining medium for the 90 sweeper. When it is desired to operate either the sweeper or the vacuum cleaner independently, the nozzle 22 is removed, when the sweeper may be detached at its rear end from the supporting pintle 57. If desired, 95 the handle bail 55 may have means of connection to the elongated handle 27 above referred to, and with this in view I provide on the bail 55 a coupling member 62 having a projection 63 exteriorly threaded and adapted to be engaged by interior threads 64 in the terminal of said handle 30. The sweeper is reversible, and a recess is provided in both the projection 59 and the nozzle 22 adapted for the reception of the 100 projection 63 of the handle of the sweeper, regardless of which end of the sweeper is positioned foremost, the said recesses being indicated by the numerals 65 and 66 respectively. A yieldable buffer 67 as of cord 105 projects substantially entirely around the 110 sweeper device as shown.

In operation if it is desired to utilize the combined machine for both sweeping and suction cleaning purposes the parts are assembled as illustrated in Figs. 1 and 2, and by imparting back and forth movement through the medium of the push handle 28 the bellows are operated to suck in the dust and the sweeper is also operated to pick up 115 lint, threads, pins, or other heavier particles from the surface. The sweeper is capable of a slight tilting action to the end that one or the other of the drive wheels is in tight frictional contact with the surface 120 and the brush wheel when the sweeper is 125

5 moved in one direction, while the other wheel readily rides over said surface, whereas in the return movement of the device the reverse action takes place, as is obvious. As-
10 suming now that it is desired to utilize either the sweeper or the vacuum cleaner independently, the operator swings the bail 24 about its pivot, thereby releasing the nozzle 22, and for convenience in this operation the device is set upon its rear end. The nozzle having been removed, the sweeper is released at its rear end from the pintle 57, and may have applied thereto if desired the push handle 30.

15 I claim:

1. In combination, a suction cleaner, a carpet sweeper, one of said devices being arranged below and connected to the other for simultaneous movement and operation, 20 and means whereby said devices may be bodily detached one from the other as complete units whereby they are independently operable, the one as a suction cleaner and the other as a carpet sweeper.

2. In combination with a vacuum cleaning machine having a dust box, a dust inlet nozzle, vacuum creating means and a supporting wheel, of a carpet sweeper having a dust chamber, a brush and driving wheels, and 30 means for detachably connecting the carpet sweeper to the vacuum cleaning machine below the dust box between the said inlet nozzle and supporting wheel.

3. In a carpet cleaning machine, the combination of vacuum cleaning means including a portable frame, vacuum creating means, inlet nozzle and supporting wheel, of a sweeper including a brush and driving means therefor, means for detachably connecting said sweeper to the vacuum cleaner whereby they are operable together or either the vacuum cleaner or the sweeper may be independently operated when removed, and the said sweeper being independently movable vertically when positioned on the vacuum cleaner.

4. In combination with a vacuum cleaner having vacuum creating means, a dust box, a supporting wheel and dust inlet nozzle, the 50 nozzle being supported at one end, of a sweeper comprising a casing, supporting wheels, a brush and dust collecting chamber, and attaching devices one on the vacuum cleaner frame and the other on the inlet nozzle adapted to engage opposite ends of the sweeper casing.

5. In combination with a vacuum cleaner having vacuum creating means, a dust box, a supporting wheel and dust inlet nozzle, the 60 nozzle being supported at one end and the wheel at the opposite end, of a sweeper comprising a casing, supporting wheels, a brush and dirt collecting chamber, said nozzle

being removable and having an attaching means to engage the sweeper casing and 65 maintain the latter in position, the sweeper being rendered detachable by the removal of the nozzle.

6. In combination with a vacuum cleaner having vacuum creating means, a dust box, 70 a supporting wheel and dust inlet nozzle, the nozzle being supported at one end and the wheel at the opposite end, of a sweeper comprising a casing, supporting wheels, a brush and dust collecting chamber, a loose 75 connection between the vacuum cleaner and said sweeper permitting the latter to bodily move independently vertically, and a yieldable member interposed between the top of the sweeper and the bottom of the dust box. 80

7. In combination, a vacuum cleaner, a carpet sweeper, retaining means on one of said devices for the other, means whereby said devices may be separated and each operated as independent units, and one of said 85 devices forming in effect, a cover overlying the top and ends of the other.

8. In combination, a vacuum cleaner having a dust box, vacuum creating means, a dust inlet nozzle at one end, and a supporting wheel at the opposite end, a carpet sweeper adapted to be positioned below the dust box between the nozzle and supporting wheel, the said sweeper device being detachable relative to the vacuum cleaner device, 95 and means on the cleaner to engage the sweeper and retain the same in place, said means being operable regardless of which end of the sweeper is positioned foremost.

9. In a portable device of the character 100 described, the combination of a horizontally disposed dust box, vacuum creating means positioned on the top of the dust box, a dust inlet nozzle forming a closure for the front end of the dust box, said nozzle projecting 105 downward a considerable distance below the bottom of the dust box and having in its lower edge a dust inlet slot communicating with the dust box, a supporting wheel at the rear end of the casing, a wall projecting 110 downwardly below the dust box in advance of the wheel, a sweeper of a size to fit in the space below the dust box between said downwardly projecting wall and nozzle, pintles 115 projecting inward from said wall and nozzle, and opposite ends of the sweeper casing having a recess to engage said pintles, and the nozzle being detachable whereby the sweeper may be bodily detached.

10. In a portable device of the character 120 described, the combination of a horizontally disposed dust box, vacuum creating means positioned on the top of the dust box, a dust inlet nozzle forming a closure for the front end of the dust box, said nozzle projecting 125 downward a considerable distance below the

bottom of the dust box and having in its lower edge a dust inlet slot communicating within the dust box, a supporting wheel at the rear end of the casing, a wall projecting downwardly below the dust box in advance of the wheel, a sweeper of a size to fit in the space below the dust box between said downwardly projecting wall and nozzle, pintles projecting inward from said wall and nozzle, and opposite ends of the sweeper casing having a recess to engage said pintles, the recesses being of a size to permit the

sweeper to have bodily movement vertically, and to be, of its own weight, maintained in operative engagement with the surface, and the nozzle being removable to disengage one end of the sweeper whereby the latter may be detached.

In testimony whereof I affix my signature in presence of two witnesses.

MORRIS S. WRIGHT.
